Patented Mar. 1, 1927.

UNITED STATES PATENT OFFICE.

CHARLES H. KIRBY, OF DETROIT, MICHIGAN.

MOLD FOR CASTING PISTONS.

Original application filed May 21, 1923, Serial No. 640,565. Divided and this application filed January 18, 1926. Serial No. 82,144.

The invention relates to mold for the casting of pistons and is a divisional of the application bearing Serial No. 640,565, filed May 21, 1923.

5 The invention is particularly applicable to the casting of piston blanks of such a structure as may be readily machined to form pistons of a special type, wherein the skirt is longitudinally slotted forming flexible segments depending from an integral head portion.

10 One of the objects of the invention is to provide a mold for obtaining a hollow blank closed at the opposite ends and provided 15 on the interior with reinforcing ribs for strengthening the cast structure.

Another object is to provide a mold for forming a single hollow blank from which 20 two pistons may be obtained.

25 A further object is to provide a mold having a core arranged centrally therewithin and supported by core prints extending into the portion of the mold corresponding to the space between the segmental skirts of the piston.

30 A still further object is to provide means for aligning two oppositely disposed cores and for securely supporting the same in axial alignment at points midway between the ends so that two piston blanks will be cast as a single structure closed at opposite ends.

These and other objects are obtained by the novel construction hereinafter described 35 and illustrated in the accompanying drawing, wherein:

Figure 1 is a side elevation of a piston blank shown partly in section.

Figure 2 is a cross section thereof showing 40 the interior reinforcing ribs.

Figure 3 is a longitudinal section through a mold for forming the blank of Figure 1.

Figure 4 is a plan view of the mold with the upper half removed.

45 Figure 5 is a cross section on the line 5-5 of Figure 3.

Figure 6 illustrates a modified method of aligning the cores.

The double piston blank A, shown in Figure 1 is of substantially cylindrical contour and is closed at opposite ends B and B' respectively, in order to form the heads of two separate pistons when the blank is severed into two pieces. The blank is provided

55 with diametrically opposite cut away portions C, leaving between the same the segmental skirts D. A ring E of greater thickness than the rest of the blank connects the segmental skirts D and this ring portion may be removed after the piston blanks are 60 machined, thereby forming the two pistons into a structure having freely flexible segmental skirts, or it may be left integral with the segmental skirts and the blank cut away centrally of the ring to form pistons in accordance with my co-pending application Serial No. 19,502, filed March 31, 1925. The interior of the blank A is preferably cast to the form of the finished piston so that no further machining is necessary on the inside 70 of the blank and, for the type of piston disclosed, it is preferable to provide the reinforcing ribs F in the opposite head portions B and B' and the longitudinal extending ribs G on the segments D. Piston pin bosses 75 H are also arranged on opposite sides of the ring E.

The mold for casting the blank of Figure 1 is preferably made in two parts, J and J', 80 each of which has a mold cavity corresponding to the outer contour of the blank A. K represents the core which is arranged within the cavities in the mold and has its outer surface complementary to the interior structure of the piston. The core K is preferably 85 made in two sections K' and K², each being provided with core prints L and L', extending outwardly from the core on diametrically opposite sides and supported in the upper and lower halves of the mold at points 90 corresponding to the cut away portions C of the blank. It is important that the cores K' and K² should be accurately aligned, in order that the walls of the pistons at opposite ends of the blank will be of equal 95 thickness and for this purpose a suitable interlocking connection M is provided extending into the recesses N in the respective cores. It is obvious that this connection 100 might be made integral with one of the cores if desired, and that the projecting portion thereof may be cylindrical as shown in Figure 3, or tapering as shown in Figure 6.

From the above description it will be apparent that the cores K' and K² are supported at their inner ends and that the portions forming the interior of the heads of the pistons project in opposite directions 105

from the core prints and are not further supported by the outer mold. This arrangement permits of accurately locating the cores with respect to the mold cavity so as to form the piston walls of uniform thickness, because each of the oppositely projecting cores serves to balance the other. The feature of interlocking the cores in axial alignment is therefore of great importance in obtaining castings of uniform thickness. In the particular construction illustrated the core prints L on the respective cores K' and K² are separated from each other to provide an annular cavity for the ring E. However, it is to be understood that my invention in certain of my broader aspects is not limited to this particular construction. Thus my invention contemplates broadly the formation of a mold for a double piston blank where the core is supported intermediate the opposite ends of the piston and has projecting portions extending oppositely into the respective heads.

What I claim as my invention is:

- 25 1. In a mold for casting a piston blank, the combination with an outer mold having a cavity therein corresponding to the outer contour of two oppositely disposed axially aligned pistons and a core supported in said outer mold at a point intermediate its ends, said core projecting from said support in opposite directions and having its surfaces corresponding to the inner contour of a reinforced hollow piston.
- 30 2. In a mold for casting a piston blank, the combination with an outer mold having a substantially cylindrical cavity therein, a core axially arranged within said cavity and core prints extending from said core between

the opposite ends thereof, and supported by 40 said outer mold.

3. In a mold for the formation of two oppositely disposed integral piston castings, the combination of an outer mold having a mold cavity, a pair of oppositely disposed 45 adjacent cores supported in said outer mold and means for aligning said cores in said mold.

4. In a mold for the formation of two oppositely disposed integral piston castings, 50 the combination of an outer mold having a mold cavity, a pair of oppositely disposed adjacent cores supported in said outer mold and a longitudinal projection on one of said cores engaging a recess in the other core for 55 aligning said cores in said mold.

5. A mold for piston castings comprising upper and lower mold sections together forming a mold cavity, a horizontal core arranged within said cavity and core prints 60 extending from said core and supported by the upper and lower sections respectively, said core having portions projecting in opposite directions from said core prints.

6. A mold for piston castings comprising 65 an outer section having a mold cavity therein and a core arranged within said cavity supported intermediate its ends by said outer molds, said core having similar portions projecting in opposite directions from 70 said support and otherwise disconnected from said outer section, the oppositely projecting portions being connected together to provide a balanced core construction.

In testimony whereof I affix my signature:

CHARLES H. KIRBY.
